UNITED STATES PATENT OFFICE.

MARTIN A. GRONSETH, OF SUPERIOR, WISCONSIN.

DISPLAY-TRUNK.

1,325,843.

Specification of Letters Patent. Patented Dec. 23, 1919.

Application filed October 25, 1917. Serial No. 198,385.

To all whom it may concern:

Be it known that I, MARTIN A. GRONSETH, a citizen of the United States, residing at Superior, in the county of Douglas and State 5 of Wisconsin, have invented certain new and useful Improvements in Display-Trunks, of which the following is a specification.

This invention relates to display trunks having for its primary object to generally 10 simplify and improve the construction and operation of devices of this character, as well as to increase their efficiency.

A further object of the invention is to provide a display trunk which will occupy 15 but a small amount of room when closed or inoperative, but which affords a great amount of space for display purposes when the supporting leaves are extended.

A still further object of the invention is 20 to provide a trunk of the character mentioned which includes a plurality of extensible supporting leaves, the leaves being so constructed and arranged as to occupy but a small amount of space within the trunk, 25 the said leaves, when extended, providing a great amount of surface for display purposes, and which are supported in such manner as to prove sufficiently strong to withstand the weight to which they will be subjected when used for displaying goods.

A still further and particular object of 30 the invention is to provide a trunk of the character mentioned which shall be of light weight, and inexpensive construction, which 35 is capable of being easily and quickly operated so as to be extended or collapsed, which has its various movable parts so constructed and assembled as to minimize the opportunity for wear or breakage, and which provides a maximum amount of space for storage purposes.

With these objects in view, together with others which will appear as the description 40 proceeds the invention resides in the novel 45 formation, combination, and arrangement of parts, all as will be described more fully hereinafter, illustrated in the drawings and particularly pointed out in the claim.

In the drawings:—

50 Figure 1 is a vertical longitudinal sectional view taken through a display trunk constructed in accordance with my invention, the trunk being shown in closed or inoperative position.

55 Fig. 2 is a similar view on a slightly reduced scale, and showing the manner in

which the extension leaves are withdrawn from the trunk when it is desired to use the same as a display table.

Fig. 3 is an elevation showing the positions the leaves and legs will assume when the trunk is in set up position. 60

Fig. 4 is an enlarged detail fragmentary view taken through the upper end of the trunk, and illustrating the manner in which 65 the innermost of the extension leaves is slidably supported within the trunk.

Fig. 5 is a similar view taken horizontally through one corner of the trunk.

Fig. 6 is an enlarged fragmentary side 70 elevation of the outer end of one of the leaves, and illustrating the manner in which the supporting legs are secured thereto, and

Fig. 7 is a fragmentary elevation illustrating the manner in which the brace rod 75 is attached to the supporting legs.

The trunk used in carrying out this invention is indicated generally at 10, and comprises a hollow body formed of any suitable material and of any desired size, being 80 closed at its upper end by a lid or cover indicated at 11. The lid 11 is secured to the body of the trunk by extension hinges indicated at 12, so that the said lid when swung to open position will drop slightly 85 below the upper edges of the trunk body.

Arranged in spaced parallel relation upon the opposite sides of the trunk and upon the interior thereof, are longitudinally disposed trackways 13. These trackways are formed 90 preferably of light metal, and constitute bars a trifle longer than the height of the trunk. Each of the bars is provided with a longitudinal slot 14, and each bar is provided at its extremities and intermediate its 95 ends with outwardly extending legs 15, through which retaining screws or nails 16 are driven to secure the trackway firmly to the trunk sides. It will be observed that the legs 15 extend inwardly beyond the plane 100 of the bar, so that the latter will be held in spaced parallel relation with the trunk sides. It will also be observed that the trackways are spaced slightly beyond the front and rear of the trunk body. 105

The opposing trackways of each end of the trunk body support between them the inner end of an extensible leaf 18, the said leaf being provided at its inner end with outwardly and oppositely extending studs 110 19 engaged within the grooves 14 of the trackways. The leaf 18 is of a length pref-

erably equal to the height of the trunk body, and by reason of the particular manner in which the said leaf is arranged within the body, the same is capable of being freely 5 slid into and out of the same. The leaf 18 has hinged to it at its outer end as at 20 the inner extremity of an extension leaf 21, the latter being of substantially the same dimensions as the leaf 18. It will be ob- 10 served that the table leaves 18-21 when extended are disposed in the same general horizontal plane, and the inner extremity of the leaf 18 rests upon the upper edge 15 of the trunk body 10. When it is desired to fold the leaves and to inclose the same by the trunk, the leaf 18 is swung upwardly, and the leaf 21 swings upon its hinge 20 so as to lie against the under face of the 20 first mentioned leaf. The leaves may be 25 formed of any suitable material, it being preferred, however, that the same be constructed of thin, light, and yet durable composition board, and may, if desired, be re- 30inforced in any preferred manner so as to lend strength and rigidity to the table when the latter is in set up position. By constructing the table leaves of thin material, the same will occupy but a small amount of space within the trunk body, thereby enabling the trunk body to be used as a storage place for goods.

The outer extremities of the leaves 21 are provided with legs 22 to support the same in proper extended position. These 35 legs may be formed of light, strong metal, and each is provided at its upper end with a right angularly extending portion 23. The right angularly extending portions 23 are pivoted as at 24 to the outer ends of 40 brackets 25 secured to the opposing edges of the leaves 21 at the free ends thereof, and by so connecting the legs to the leaves, it is obvious that the said legs may be folded upwardly so as to lie alongside of the edges 45 of the leaves 21 when the table is collapsed. To maintain the legs 22 in supporting position, the said legs are each provided with a brace member 24' pivoted as at 25' at 50 one end to the legs below the upper end thereof. The free ends of the brace bars may be hooked as shown, so as to engage over outwardly extending studs or pins 26 on the sides of the leaves 21. The legs may be of a length equal substantially to the 55 height of the trunk so that the tables will be supported in proper horizontal position.

By arranging the trackways 13 upon the ends of the trunk body and slightly inwardly from the front and rear thereof, a

suitable space is provided between the front 60 and rear and the adjacent trackways, for the accommodation of the tables when the latter are collapsed. The remaining space in the trunk may be utilized for the storage of trays indicated at 30, and in which goods 65 may be stored. It is obvious, therefore, that a trunk so constructed permits of the accommoda- 70 tion of a relatively great amount of goods, as the folded tables occupy but a small amount of space.

When the trunk is closed, and not in use as a display medium, the table sections will be housed within the same in the manner illustrated in Fig. 1. When it is desired to use the display leaves, the latter are withdrawn from the trunk in the manner shown in Fig. 2, and the parts thereof are swung to the positions shown in Fig. 3. A great amount of space is thus provided for display purposes, and the trays 30 may remain in 80 the trunk body or may be removed therefrom as desired.

While the present is a disclosure of what is believed to be the preferred embodiment of the invention, it is to be understood that 85 the invention is not limited thereto, but that various changes in the minor details of construction, proportion, and arrangement of parts may be resorted to if desired without departing from the spirit of the invention 90 as defined by the appended claim.

I claim:—

A trunk, comprising a body open at the top, track ways upon the inner faces of opposite sides of the body adjacent the front 95 and back thereof, leaves having sliding and pivoted connection at their inner ends with the respective track ways and adapted to lie close against the front and the back of the said trunk when slid therein, other leaves 100 hinged to the outer ends of the first mentioned leaves and adapted to fold thereagainst and slide therewith into the trunk, and supporting legs hinged to the second leaves to fold therewith against the first 105 mentioned leaves to slide therewith into the trunk, said leaves being of sheet-like formation, and the leaves and the supporting legs hinged thereto nesting in the spaces formed between the sliding leaves and the 110 walls of the trunk parallel therewith when said parts are in folded position.

In testimony whereof I affix my signature in presence of two witnesses.

MARTIN A. GRONSETH.
